UNITED STATES PATENT OFFICE

RAY E. BAUDER, OF CHICAGO, ILLINOIS

VISIBLE FILE

Application filed August 2, 1930. Serial No. 472,576.

This invention relates to a visible filing system and equipment therefor.

One object of my invention is to provide a container having a sight opening in its front wall whereby the memoranda filed in the container will be visible through the sight opening as brought adjacent the same in the use of the file without requiring the removal or withdrawal of the container from its enclosing cabinet or casing.

Another object of my invention is to provide novel folders for use in such container whereby the memoranda to be filed in the containers may be inserted in the folders.

15 A further object of my invention is to provide the folders with translucent or transparent front walls whereby the memoranda behind the same will be visible through said walls as the folders are brought adjacent to the sight opening.

20 A further object of my invention is to make the rear walls of the folders opaque so as to provide suitable background for the memoranda therein and to render invisible all folders behind the one at the sight opening.

25 A further object of my invention is to provide the folders with indicia of the character required for the system with which the folders are used, so that such indicia will be visible through the sight opening of the container as the folders are brought opposite the same.

30 A further object of my invention is to have the indicia arranged on both front and rear walls of the folders so that the presence of memoranda within the folders will be forcibly indicated by the breaking up or disturbing of the continuity of the indicia on said walls.

35 A still further object of my invention is to provide the casing for the container with changeable indicia associated with that on the folders so that the file may serve as a daily or other reminder by which matters requiring attention at stated intervals or predetermined periods of time may be attended to when required.

The invention consists further in the matters hereinafter described and claimed.

In the accompanying drawings:

50 Fig. 1 is a perspective view of a file cabinet

of the single drawer type embodying the features of my invention;

Fig. 2 is a similar view with one corner of the cabinet broken away to show the indicating tape or band to be hereinafter referred to; 55

Fig. 3 is a perspective view of the front of the drawer, a portion of which is broken away for illustrative purposes;

Fig. 4 is a top plan of the drawer removed from its casing to show the folder-supporting 60 means therein;

Figs. 5 and 6 are perspective views of one of the folders in set-up form, memoranda being inserted in the folder in Fig. 6, and omitted in Fig. 5; and 65

Fig. 7 shows a folder in spread-out or blank form.

In the drawings, 1 indicates a file box or cabinet of a type having a single sliding drawer 2. The front wall 3 of the drawer is 70 of a size to completely close the opening at the front of the box when the drawer is closed as usual in equipment of this kind. The wall 3 is provided within its margins with an opening 4 which may or may not 75 contain a transparent cover 5 depending upon how much protection is desired for the contents of the drawer. In the drawings, I have shown a glass cover 5 fitted within the opening 4, although celluloid or other transparent 80 material may be used, if desired.

In the drawer are a number of folders 6, 6 each of a size to fit within and stand substantially upright in the drawer when in use. Each folder, in accordance with my invention, 85 comprises front and rear walls 7, 8 of substantially the same size and shape and a laterally narrow connecting wall 9. The latter is at the base or lower edge of folder and forms a flat bottom wall therefor on which the folder rests when placed in the drawer. In the drawings, I have illustrated the walls integrally connected, being made from a single blank as shown in Fig. 7, although the walls may be made separate and afterwards 90 joined in any suitable manner to make the folder a single unit. When made from a blank, the sheet material is scored to divide the blank into the requisite sections for the 95 walls 7, 8 and 9. 100

It is preferred to make the folders of translucent material, such as celluloid, the front wall 7 being left translucent or transparent if material of that character is employed.

5 The rear wall 8 is colored or otherwise treated or prepared to make it opaque or semi-opaque as indicated by the shading in Figs. 5 to 7.

Printed on the front wall 7, on either its front or rear face, in double outline or open 10 form is a relatively large character 10, preferably a figure, such as "28", indicative of the day of the month. A similar character 11 is printed on the rear wall 8 in closed or solid form and positioned to register with the outline of the character on the front wall 7 when the folder is set up for use. It is essential 15 that the solid figure 11 be printed in a color contrasting to that of the color of the background afforded by rear wall 8 so that the figure 11 will be readily visible through the translucent wall 7 when there is nothing between the walls to cover or hide the figure on the background, as shown in Figs. 1 and 5.

In use, the folders 6 are placed in upright 20 position in the drawer 2, one behind the other, with their front walls 7 foremost. When the file is used as a daily visible reminder, there will be a folder for each day of the month with the number designations for the several days 25 on the respective folders. The folders will be arranged in the drawer or container 2 in chronological order and be supported in upright position on their bottom walls 9, the latter being wide enough for the purpose.

30 The bottom walls 9 will also normally keep the front and rear walls 7, 8 of the respective folders sufficiently apart to provide pockets between them to receive memoranda, such as slips of paper or cards 12 which may be 35 dropped into the pockets through the open upper ends of the folders without the necessity of fingering the folders to open them.

To facilitate locating the folders in the drawer for dropping memoranda into the same 40 without being required to lift the folders from the drawer or spread them apart to see the indicias on their front or rear walls, I provide the rear wall 8 of each folder with an 45 upstanding integral tab 13 at its upper edge

50 on which is printed or otherwise applied a number or other index corresponding to that on the body of the folder, as clearly shown in Figs. 5 to 7. The folders stand upright in the drawer by reason of the stiffness of the 55 material of which they are made and also due to the support afforded by the side walls 14, 14 of the drawer with which the folders contact by being made of a width to extend between them.

60 Memoranda of any size up to the size of the folder may be dropped into the same, and will be visible through the translucent front wall 7 of the folder and be thrown out into visible relief by the background provided by 65 the opaque rear wall 8, as indicated in Fig. 6.

The memoranda within the file call attention to themselves forcibly by the breaking up of the color combination employed in the printing of the indicia. This is an important feature of my invention and is well illustrated in 70 Fig. 6. As there shown, the memoranda 12 extend over a portion of the solid figure 11 on the rear wall 8 of the folder and thus breaks the continuity of the figure through the double outline 10 on the front wall 7 of the folder. This calls attention to the fact that there are 75 memoranda in the folder and advises the user of the file that the date folder in view through the opening 4 in the front wall of the drawer needs attention, on the date displayed by the folder. The folders will be adjusted from day to day to position the current folder at the opening in the front of the drawer and as the folders containing memoranda appear, 80 the user of the file may attend to the same on the date set for the purpose. Because of the opaqueness of the rear walls 8 of the folders, any memoranda in the folders for the succeeding days will not be revealed 85 through the opening at the front of the drawer and thus only the memorandum in the current folder will be visible through the front of the drawer. If at any time memoranda for several days are required to be visible through the front of the drawer, folders having both transparent front and rear sections may be employed.

To assist in holding the folders in upright 90 position in the drawer, I may provide the side walls 14, 14 of the drawer with inwardly extending prongs or projections 15, 15, preferably pressed inward from the metal of the walls and arranged to permit the folders to ratchet over them as the folders are moved forward in bringing the current date folder 95 to view at the opening at the front of the drawer. The prongs in pointing forward offer resistance to any backward movement to the folders and thus hold them upright for the insertion of the material to be filed in them and also for holding the current folder upright at the opening at the front of the drawer for clear display of the date thereon and the memoranda therein.

110 The box or cabinet 1 is provided in its front wall with openings 16, 17, on opposite sides of the drawer 2. Behind these openings are moved endless tapes or bands 18, 19, one 115 for each opening, and on which are printed the names of the months and the names of the days of a week, respectively, as shown in Figs. 1 and 2. The tapes are supported by and arranged over suitable rolls mounted in the box in a manner to permit the tapes to be 120 moved to present the desired day and month designations at the openings so as to indicate the particular month and the days thereof for which the folders are being used. Each 125 tape is movable by a thumb wheel 20 ar-

ranged for access from the exterior of the cabinet as shown in Figs. 1 and 2.

While I have shown and described herein the folders marked with numbers representative of days of a month, it is to be of course understood that other indicia could be marked on the folders depending on the nature of the filing system with which the folders are to be used. In an alphabetical system, the 10 folders would be marked with letters or combinations of letters, whereas in some other system the indicia required for such a system would be employed. The feature of having the front walls of folders translucent or 15 transparent would be employed for all systems because of the visibility rendered for the memoranda or memorandum contained in the pockets provided by the folders. As a daily visible reminder, the visible feature afforded by the folders is an effective one, especially when used with a drawer or container having an opening in its front wall so that the folders will be visible without opening the drawer as the folders come to view 20 at the opening. The folders are simple in construction, easy and inexpensive to make and install, and usable in the manner of the regular filing systems. This feature in itself is an advantage because the user is not 25 required to master a new or complicated system.

The details of structure and arrangement of parts shown and described may be variously changed and modified without departing from the spirit and scope of my invention.

I claim as my invention:

1. A folder for use in a filing system, comprising front and rear walls connected together to form a memoranda-receiving pocket, one of said walls being translucent to render visible therethrough the memoranda in the pocket, said wall having indicia thereon.

45 2. A folder for use in a filing system, comprising front and rear walls connected together to form a memoranda-receiving pocket, one of said walls being translucent to render visible therethrough the memoranda in the pocket, said wall having indicia thereon in double outline.

3. A folder for use in a filing system, comprising front and rear walls connected together to form a memoranda-receiving pocket, one wall being translucent and the other opaque, said walls having similar indicia thereon arranged to register when the folder is set up for use.

4. A folder for use in a filing system, comprising front and rear walls connected together to form a memoranda-receiving pocket, one wall being translucent and the other opaque, said walls having similar indicia thereon arranged to register when the folder is set up for use, the indicia on the

respective walls being in open and closed form, respectively.

5. A folder for use in a filing system, comprising front and rear walls connected together to form a memoranda-receiving pocket, the front wall being translucent and the rear wall being opaque, said walls having similar indicia thereon arranged to register when the folder is set up for use, the indicia on the front wall being in double outline and the indicia on the rear wall being in solid form.

6. A folder for use in a filing system, comprising front and rear walls connected together to form a memoranda-receiving pocket, the front wall being translucent and having indicia thereon, and a tab on the rear wall and projecting beyond the same, said tab having indicia thereon corresponding to those on the front wall.

7. A folder for use in a filing system, comprising front and rear walls and a relatively narrow connecting wall located at the lower edge of the folder and providing a base therefor and a spacer for the front and rear walls, one of said walls being translucent and the other opaque.

8. A container adapted for use in a filing system, and having a front wall with a sight opening therein, and means in the container adapted to receive a sheet of memoranda and to display the same through said sight opening as the sheet is brought adjacent thereto.

9. A container adapted for use in a filing system, and having a front wall with a sight opening therein, and means in the container for separating memoranda filed therein into groups, said means being translucent and rendering visible through the sight opening memoranda of the first group as the latter are brought opposite the sight opening.

10. A container adapted for use in a filing system, and having a front wall with a sight opening therein, and folders in the container having connected front and rear walls forming pockets to receive memoranda, the front walls of the folders being translucent to render visible through the sight opening the memoranda in a folder as it is brought opposite the sight opening.

11. A container adapted for use in a filing system, and having a front wall with a sight opening therein, and folders in the container having connected front and rear walls forming pockets to receive memoranda, the front walls of the folders being translucent to render visible through the sight opening the memoranda in a folder as it is brought opposite the sight opening, the rear walls of the folders being opaque to render invisible through the sight opening the memoranda in those folders to the rear of the one at the sight opening.

12. A file cabinet, comprising a casing, a container therein and having a sight opening

in its front wall, separators in the container for separating memoranda filed therein into groups and having indicia visible through said sight opening as the separators are brought opposite the same in the use of the file, and a changeable indicator at the front of the casing and having indicia thereon associated with those on the separators.

18. A file cabinet, comprising a casing, a container therein and having a sight opening in its front wall, separators in the container for separating memoranda filed therein into groups and having indicia visible through said sight opening as the separators are brought opposite the same in the use of the file, a movable tape carried by the container at the front of the same and having indicia thereon associated with those on the separators, and means whereby the tape may be moved.

14. A file cabinet, comprising a casing, a container therein and having a sight opening in its front wall, separators in the container for separating memoranda filed therein into groups and having indicia visible through said sight opening as the separators are brought opposite the same in the use of the file, and a changeable indicator at the front of the casing and having indicia thereon associated with those on the separators, said separators being translucent to make visible therethrough the presence of memoranda behind the same.

15. A file cabinet serving as a daily remainder, comprising a casing, a container therein and having a sight opening in its front wall, separators in the container for separating memoranda therein into groups, there being a separator for each day of a month and having a number thereon representative of the day of the month and visible through said sight opening as a separator is brought opposite the same in the use of the file, and a changeable indicator at the front of the container and usable with said separators, said indicator having indicia thereon representative of the names of the months and the names of the days of a week, respectively.

16. A folder for use in a filing system formed from a blank of translucent sheet material and divided into a number of sections constituting the front, rear and connecting walls of the folder, the section forming the front wall being left translucent while the section forming the rear wall is treated to render it opaque.

17. A folder for use in a filing system formed from a blank of translucent sheet material and divided into a number of sections constituting the front, rear and connecting walls of the folder, the section forming the front wall being left translucent, while the section forming the rear wall is treated to render it opaque, said front and rear walls

having corresponding indicia thereon disposed to register when the folder is set up for use.

In testimony whereof I affix my signature.
RAY E. BAUDER.
